DEVICE FOR ELECTRICAL PURIFICATION
OF GASESGeorg Brion and Johannes Krutsch, Freiberg,
GermanyApplication September 9, 1929, Serial No. 391,503
In Germany September 17, 1928

5 Claims. (Cl. 183—7)

When gases are made conductive by percus-
sion- or thrust-ionization, the ions and electrons
thus formed move in the electric field toward
the electrodes on which they deposit their electric
charge. The voltage between the electrodes serves
two purposes. The first of these is the produc-
tion, in the whole region or in a certain part of
it, of the field which is necessary for the ioniza-
tion. The second is the attraction of the ions
10 and electrons to the electrodes, thereby setting
up a current. This double duty of the voltage
often leads to difficulties and waste of power.
For example, where two electrodes are placed at
a considerable distance from each other, a very
15 high voltage is necessary for the ionization, where-
as the ions and electrons formed could be moved
toward the electrodes by a much lower voltage.

In order to overcome this difficulty it has been
suggested to subject the gas first to an ionizing
20 alternating voltage of sufficient strength to effect
the ionization and then to subject the gas to the
action of a pair of electrodes across which is im-
pressed a low direct current voltage to cause the
ions and electrons to travel to the electrodes. In
25 such cases, however, it is necessary that the gases
have a certain speed of travel from the ionization
field to the precipitation field. If the gases are
stagnant, the ions and electrons will travel to the
ionization electrodes instead of the precipitation
30 electrodes. This action is very detrimental to
the purification of gas by this method since it is
essential that the impurities be deposited on the
precipitation electrodes rather than on the ionization
electrodes. Moreover, the alternating volt-
35 age used in this method must necessarily be so
high that there is considerable danger of sparking
which is apt to cause an explosion when a dust-
laden gas is being treated.

The object of the present invention is to over-
40 come these difficulties by superimposing the ion-
ization field and the precipitation field upon each
other, preferably by enclosing the ionization field
in the precipitation field. By this arrangement,
stagnant gas can be purified. Thus our inven-
45 tion has in view to effect the charging of the
particles suspended within the gas by an opera-
tion involving two steps or stages and the use of
two separate voltages and electric fields produced
thereby. One of these voltages effects the ion-
50 ization of the gas, whereas the charging itself oc-
curs in the field due to the other voltage which
may be separately regulated and may at the same
time, convey the charged particles to the precipi-
tating electrodes. The ionization voltage and the
55 precipitation voltage may also be impressed by

the same source of power and be mutually depend-
ent upon each other, the failure of one causing
the failure of the other. With our invention we
obtain very effective precipitation and the sus-
pended particles travel with great velocity to the
precipitating electrodes so, that with an appara-
tus of short length a gas current of comparative-
ly high velocity may be purified. The apparatus
according to this invention is therefore of small
dimensions. At the same time, the electrodes may
be massive, and the very thin discharging wires
used in ordinary purifying apparatus are not nec-
essary. With this novel apparatus, the ionizing
electrodes are free from precipitated particles, so
that the working of the apparatus is not inter-
fered with by covering of the ionization elec-
trodes.

According to this invention the apparatus for
the electrical purification of gases is provided
with two sets of electrodes, fed by separate volt-
ages, the gaps and therefore the fields of these
sets being placed substantially perpendicular to
each other, and the field of one set of electrodes
serving to produce ionization and thus establish-
ing carriers of electricity, while the gas current 80
is passed along these electrodes and between the
other set of electrodes. The field of this other
set serves for carrying the carriers of electricity
through the gas, the particles within the gas thus
being charged and precipitated at the precipitat-
ing electrodes. According to this method only the
field due to the ionizer must be relatively strong.
The additional field for carrying the ions or car-
riers of electricity through the gas and for charg-
ing the particles suspended within the gas can 85
be relatively low. This additional field may be
supplied by a direct current voltage which need
not be so high that any danger of sparking can
arise. The combined action of the two fields makes
it possible to work with lower voltages by reason 90
of some action, probably of the nature of induc-
tion, which is not understood. The combined
action of the fields furthermore imparts greater
activity to the particles in the gas and, in the
case of gas purification, materially accelerates 100
the process.

In carrying out this invention it is preferable
to cover at least one of the electrodes, upon which
the ionization voltage is impressed, with a layer
of insulation and to arrange them close enough
together so as to create a strong field between
them with the voltage impressed upon them. The
electrodes upon which the direct voltage is im-
pressed are preferably large, flat, parallel surfaces
so arranged as to set up a field intersecting or 110

embracing the field set up by the ionization electrodes.

The accompanying drawings illustrate one embodiment of our invention which embodiment is to be taken as illustrative rather than limitative. Figure 1 represents a diagrammatic view of applicants' device; Figure 2 an elevation of the gas chamber enclosing the purification device. The gas chamber is designed by *c*, two precipitating electrodes parallel to the walls, by *p p*. The electrodes are electrically connected to each other and to the earth. The ionizer *i* consists of a number of parallel round rods *i¹*, *i²*, arranged in close proximity to each other and suspended within the chamber and at the same time insulated from its walls by the insulators *m*. It is important that sharp edges be avoided in order to eliminate all danger of sparking. Alternate rods are made entirely of metal having conducting surfaces. The other rods *i²* are covered with a layer of insulating material. The conducting rods, on the one hand, and the insulated rods, on the other hand, are connected in parallel. The transformer *t₁* impresses an alternating voltage on the ionizer rods. The second transformer *t₂*, in connection with the rectifier *g* and the condenser *k*, impresses a direct voltage across the precipitating electrodes and on the metal bars of the ionizer. Both sets of electrodes are arranged within the gas chamber *c*. When applying the invention for gas purification, the gas current to be purified is passed between the precipitating surfaces in the direction of the arrows the particles being ionized by the ionizer *i* and precipitated on the plates *p p* by the direct current set up between them.

Having thus described our invention and illustrated one embodiment of the same, what we claim as new and useful and desire to secure by Letters Patent is:—

40 1. In a device for electrical purification of gas, in combination, two sets of electrodes each set being separate and independent from the other, two sources of electric voltages one for inde-

pendently feeding each set of said electrodes, one of said sets of electrodes so connected as to establish a strong electric alternating field for producing carriers of electric charges, means for passing said gas along this set of electrodes, the second of said sets of electrodes so connected as to produce a second field partly superimposed and across the first of said fields for producing migration of the carriers of electric charges across the stream of gas, thus charging the particles suspended within the gas. 80 85

2. A device in accordance with claim 1 and in which a source of direct current is provided for producing said second field. 90

3. A device in accordance with claim 1, in which the ionizer consists of two parallel groups of linear conductors of different polarity, the conductors of each group being connected to each other in parallel, the conductors of both groups alternating and being arranged substantially in one plane. 95

4. A device in accordance with claim 1, in which the ionizer consists of two parallel groups of linear conductors of different polarity, the conductors of each group being connected to each other in parallel, the conductors of both groups alternating and being arranged substantially in one plane, the conductors of at least one group being covered with insulating material. 100

5. A device in accordance with claim 1, in which the ionizer consists of two parallel groups of linear conductors of different polarity, the conductors of each group being connected to each other in parallel, the conductors of both groups alternating and being arranged substantially in one plane, the electrodes of said other set consisting of two plates arranged at the sides of said ionizer, and the field between said plates and said ionizer being set up by a voltage independent from the ionizing voltage. 110 115 120
